MEANS FOR AND METHOD OF TIMING
SPRAY OPERATIONS FOR PREVENTING
SMUTTING IN PRINTING PRESSESVirgil G. Green, Chicago, Ill., assignor to Binks
Manufacturing Company, Chicago, Ill., a cor-
poration of Delaware

Application August 9, 1939, Serial No. 289,234

9 Claims. (Cl. 101—422)

The present invention relates to means for and method of timing spray operations for preventing smutting in printing presses, such as web printing presses, wherein the imprints are effected on both sides of the web as it travels through the printing couples, and has reference more particularly to the timing of the application of anti-smutting fluid upon the tympan or backing cylinder of the succeeding couple for the still wet imprint made in the previous couple.

In presses of this type, the web first passes through a couple to receive an imprint on one side of the web from the printing cylinder of that couple, the other side of the web being backed by an impression cylinder usually termed a tympan cylinder. As the web then travels to the succeeding couple, where the cylinders are in reverse order, the unimprinted side of the web is presented to the printing cylinder of this couple, and the yet wet imprinted side is presented to the tympan cylinder. The latter tympan cylinder has a tympan sheet covering and, to avoid transfer of ink upon this covering, an anti-smutting fluid, such as oil, is sprayed in a very fine spray toward the tympan, such spraying being either directly upon the surface of the covering where the particles of oil are dispersed and later distributed by a roller having a yieldable surface, or indirectly as by spraying upon a roller having a yieldable surface which in turn distributes the oil to the surface of the covering.

Heretofore, the application of the oil has been continuously during the operation of the press, stopping only when the press stopped, with the disadvantage of using too much oil for proper effect, causing a considerable amount of oil fumes in the atmosphere which are disagreeable and noxious, and also requiring the use of a large amount of compressed air for the spraying.

By the present invention, the spraying is effected automatically in given time relation to the rotation of the tympan and in given alternating or intermittent periods of time, such as for alternate revolutions of the tympan, or variables thereof. In other words, the spraying may occur for a revolution of the tympan and no spraying may occur for the next revolution, or next two revolutions, etc. On the other hand, the spray may be for any given angular movement of the tympan and spraying stopped for any other angular movement of the tympan. In this way, a minimum amount of oil is used with the result of having much less oil fumes in the air which is rendered more breathable, and much

less compressed air is necessary, thus effecting considerable economy.

As another object of the invention is the provision of a novel timing means for controlling the spraying in given time relation to the operation of the tympan referred to above.

A further object of the invention is to provide a novel adjustable means for the spraying means to afford access by the operator to certain parts

10 of the press.

Other objects, advantages, capabilities, features, and the like are comprehended by the invention as will later appear, and as are inherently possessed by the invention.

15 Referring to the drawings:

Fig. 1 is a fragmentary side view, partly in section, of a printing press embodying the invention;

Fig. 2 is a transverse view in elevation of the 20 same;

Fig. 3 is a side view of a timing device for the spraying of oil;

Fig. 4 is a view in elevation of the same;

25 Fig. 5 is a sectional view of a control valve forming part of the timing means;

Figs. 6 and 7 are fragmentary sectional views showing the use of different kinds of coverings for the tympan; and

30 Figs. 8 and 9 are diagrammatic views of the different forms and methods of applying the oil to the tympan.

Referring more in detail to the drawings, the embodiment selected to illustrate the invention is shown in connection with a web type of printing press comprising side frame portions 1 and 2 suitably supporting printing couples, of which the second couple is shown as comprising a printing cylinder 3 and a tympan cylinder 4 operated by suitable and usual means in such types

40 of press.

At the sides of the press and on the base 5 thereof are secured angle-form brackets each having a base flange 6 secured to the base 5 by bolts and an upstanding flange 7. At the upper 45 portion of the flange 7 is secured a pivot stud 8 upon which is pivoted the lower portion of an arm 9. To the lower portion of the flange 7 are secured spaced stop or abutment pins 10 against which alternately engage the lower end extension 11 of the arm 9 when swung from and to the 50 positions shown in full and dotted lines in Fig. 1 of the drawings.

At the upper end portions of the arms 9 are provided suitable apertures for the extension 55 therethrough of parallel manifolds or pipes 12

and 13 which pipes extend between the sides 1 and 2 of the press and are supported at the upper end portions of the arms 9, these pipes respectively constituting the air and material pipes or manifolds. At an end the pipes 12 and 13 are closed as by caps 14 and 15, and at the other end are connected to flexible ducts or hoses 16 and 17, respectively. The material duct 17 leads upwardly through an upper platform 18 of the press, and is connected by way of a valved connection 19 to the lower part of a material container 20, so that the material may flow by gravity through the duct 17 to the material pipe 13. The air duct 16 leads to a cam operated three-way valve 21, shown in detail in Fig. 5.

To the material pipe 13 are clamped a plurality of spaced brackets 22 each carrying a spray gun 23 which may be of the type disclosed in the copending application of Bramsen et al., Serial No. 225,974, filed August 20, 1938. Connected to the guns 23 are flexible material and air ducts 24 and 25 respectively connected to the material and air pipes 13 and 12.

The air is supplied from an air supply line 27 by way of an air cleaner 28, pressure regulator 29, electro-magnetic or solenoid operated control valve 30, and a flexible air duct or hose 31 leading and connected to the three-way valve 21.

The three-way valve 21 is shown in detail in Fig. 5. It comprises a body 32 suitably secured to a supporting bracket 33, an air inlet member 34 to which the duct 31 is connected, and an air outlet 35 to which duct 16 is connected. In the body 32 is a double valve comprising valve elements 36 and 37 connected by a stem 38, the valve element 36 normally seating on a valve seat element 39 under the force of a spring 40, and valve element 37 is normally open with reference to a movable valve seat element 41 which is normally held away from valve element 37 by a spring 42. The element 41 is tubular to provide a relief passage 43 leading to outlets 44 in the outer end portion of the element 41. To the outer end portion of element 44 is rotatably connected a roller 45 (see Fig. 3) against which a cam 46 operates to reciprocate the element 41 in the body 32 of the valve.

In operation, when the cam 46 acts against the roller 45, the element 41 is moved inwardly to close against valve element 37 to shut off passage of air to the relief passage 43, and to open valve 36-39 so as to permit air to pass by way of inlet 34 to the interior of the valve body 32 and thence out through the outlet 35. When the cam lobe 49 passes from the roller 45, the springs 40 and 42 act to close valve 36-39 and to move element 41 so as to open relief valve 37-41.

The timing device, shown in detail in Figs. 3 and 4, comprises the cam 46 secured to a shaft rotatably supported in a support 48, the cam having a 180° swell or positive lobe 49 and a 180° dwell or negative lobe 50, so that for one half revolution of the cam the lobe 49 will maintain the three-way air valve 21 open, and for the other half revolution of the cam the valve will be closed. Also secured to the shaft 47 is a pulley 51 driven by a belt 52 driven from a pulley 53 secured to the shaft 54 of the printing cylinder, the pulley 53 being half the diameter of the pulley 51 so that the latter will make but one revolution for each two revolutions of the printing and tympan cylinders 3 and 4.

The support 48 is adjustably secured to a stud 55, as by a set screw 56, rigid with an end of a Z-shaped bracket 57 bolted at its other end to an

upright 58 which is part of the side 2 of the press frame. The lower end portion of the support 48 is apertured to slidably and rotatably adjustably receive the lower round end 59 of an S-shaped bracket 60 of rod form, such lower end 59 of the bracket being secured in adjusted position by a suitable set screw 61. To the upper round end portion 62 of the bracket 60 is slidably and rotatably adjustably secured a hub 63, as by set screws 64, the hub 63 forming a rigid or integral part of the three-way valve supporting bracket 33.

The cam 46, pulley 51 and support 48, as an aggregate, are angularly adjustable about the stud 55 to obtain the proper operative relation with the three-way valve 21 as is clearly shown in Fig. 3. The bracket 66 is so adjustable in the lower part of the support 48 and the valve support 33-63 are so adjustable on the upper end portion 62 of the bracket 60 as to cooperatively associate the three-way valve 21 with respect to the cam 46, as clearly shown in Figs. 3 and 4 of the drawings.

The surface of the tympan cylinder 4 is covered with a smooth surfaced sheet 65 or a rough surfaced sheet 66, as carborundum paper. When using the sheet 65, a roller 67 with a yieldable surface, such as the pile of a pile fabric, an example of which is plush, is so rotatably mounted as to have its pile surface 68 in contact with the surface of the sheet 65, and the battery of spray guns 23 are so located as to project fine sprays 69 of oil upon the surface of the plush roll. In the case of using the rough surfaced sheet 66, the battery of spray guns 23 are so located as to project fine sprays 70 of oil directly upon the carborundum projections on the sheet 66 without the intermediary of the plush roll, but it is preferable to also use a squeeze roll 71 which has a surface of yieldable and elastic material, such as rubber, gelatin, or similar compositions, for the purpose of applying a very slight squeeze upon the points of the carborundum so as to assist in the distribution of the minute particles of oil sprayed thereon.

The plush roll 67 so rotates that its contacting surface with the tympan travels in the same direction as the adjacent surface of the tympan but the surface speed of travel of the plush roll is either slightly greater than or less than the surface speed of the tympan surface or cover, so that there will be a relative wiping action of the plush roll on the tympan while at the same time distributing the particles of oil upon the surface of the tympan cover 65. This differential travel acts to wipe away some of the ink that has been transferred to the tympan sheet from the freshly imprinted portions of the web. The surface travel of the squeeze roll 71 is in the same direction and with the same speed as the surface speed of the tympan cover 66.

The ratio of the pulleys 51 and 53 is two to one so that the spraying upon the tympan will be for alternate revolutions thereof, that is, the spray guns will spray for one full revolution of the tympan, during which the cam 46 makes a one-half revolution, and will not spray for the next full revolution of the tympan, during which the cam 46 makes its next one-half revolution. This is advantageous in that a sufficient amount of oil is sprayed during the alternate revolutions of the tympan to produce the desired effect, and there is consequently a saving of air used to atomize the material and also a saving of oil which might otherwise be wasted in the atmosphere, if the guns were spraying continuously.

The electromagnetic or solenoid operated valve 26 is connected to the operating circuit of the press so that when the press shuts down or is stopped, the valve 30 will act to shut off the air supply to the duct 31. The regulator 29 acts to control the pressure of the air to be supplied to the duct 31.

The spray gun battery 23 with its air and material manifolds 12 and 13 are as an aggregate carried at the upper end portions of the arms 9 so that the assembly may be swung back as to the dotted line position shown in Fig. 1, to afford access by the operator in the press between the couple and the assembly mentioned above. When the assembly is to be put into operation, it is swung forwardly, as to the full line position shown thereof in Fig. 1 of the drawings.

In operation the material, such as oil, flows from the container 20 by way of valve 19, duct 17, manifold 13, ducts 24 to the guns 23, where it is atomized and sprayed in a very fine spray upon the plush roll 67 or on the tympan sheet 66, as the case may be. The air under pressure flows from the supply pipe 21, by way of the cleaner 28, regulator 29, the solenoid operated control valve 30, duct 31, to the three-way valve 21. The latter is operated by the cam 46 which, when its lobe 49 opens the valve, causes the air to flow by way of the duct 16, air manifold 12, and ducts 25 to the spray guns 23. The valve 21 is open for one-half revolution of the cam 46 and closed for the other half revolution thereof, during which time spraying will be effected for one full revolution of the tympan and be stopped for the other full revolution thereof.

Figs. 8 and 9 show diagrammatically the couples, the printing and tympan cylinders 3 and 4 of the second couple being in reverse order to the printing and tympan cylinders 3^a and 4^a of the first couple, and the web W being shown in its travel in the direction of the arrows. As the web W leaves the couple 3^a-4^a, it has the wet imprint on its upper side, and as it reaches the couple 3-4 this imprint is presented to the tympan 4 while the printing cylinder 3 effects an imprint on the under side of the web. In Fig. 8 are shown the plush roll 67 and guns 23 located with reference to the tympan 4 to apply the oil to the tympan sheet 65. In Fig. 9 are shown the guns 23 spraying directly upon the tympan sheet 66, and the squeeze roll 71 below and in contact with said sheet 66.

It is to be understood that the invention comprehends other time relations than the two-to-one time relation disclosed by way of illustration herein, and also that a two-way air valve may be used in lieu of the three-way valve shown and described.

While I have herein described and upon the drawings shown illustrative embodiments of the invention, it is to be understood that the invention is not limited thereto, but comprehends other constructions, details, features, arrangements of parts, and the like without departing from the spirit of the invention.

Having thus disclosed the invention, I claim:

1. A device for timing spray operations for preventing smutting in a web type of printing press where there is contact of a freshly imprinted portion of the web with the tympan sheet covering the tympan cylinder of the couple for effecting an imprint on the opposite side of the web from that bearing said freshly imprinted portion and wherein there are spray guns alined along the tympan to project oil in finely atomized form for application to said sheet, a pressure air supply means is connected to said guns, and an oil supply means is connected to said guns; the combination of a cam operated valve in said air supply means, a cam operatively associated with said valve and having a cam lobe for operating said valve, means operatively connected to said couple and said cam for operating said cam, said lobe being of such length as to hold said valve open for the duration of a given angular movement of said tympan and to close said valve during another given angular movement of said tympan.

5 10 15 20 25 30 35 40 45 50 55 60 65 70 75

2. A device for timing spray operations for preventing smutting in a web type of printing press where there is contact of a freshly imprinted portion of the web with the tympan sheet covering the tympan cylinder of the couple for effecting an imprint on the opposite side of the web from that bearing said freshly imprinted portion and wherein there are a battery of spray guns alined along the tympan to project oil in finely atomized form for application to said sheet, a pressure air supply means connected to said guns, and an oil supply means connected to said guns; the combination of a cam operated valve in said air supply means, a cam operatively associated with said valve and having given angular degrees of positive and negative cam lobes, a reduction speed drive means operatively connected to said cam and to said couple with a speed reduction ratio in the proportion of said given angular degrees of said lobes whereby said cam makes a part revolution for each revolution of said tympan, said cam lobes being of the extent for alternately opening and closing said valve for successive given angular movements of said tympan whereby the oil is sprayed for a given angular movement of said tympan and is stopped for another given angular movement of said tympan.

3. A device for timing the application of oil for preventing smutting in a web type of printing press where there is contact of a freshly imprinted portion of the web with the tympan sheet covering the tympan cylinder of the couple for effecting an imprint on the opposite side of the web from that bearing said freshly imprinted portion and in which are a battery of spray guns alined along the tympan and so located as to project oil in finely atomized form for application to said sheet, and a rotating roller having a yieldable surface in contact with said sheet for distributing the sprayed particles of said oil over the surface of said sheet; the combination therewith of means for controlling the time of spraying in relation to the rotation of the tympan, including means driven by the couple to cause the guns to spray intermittently for given angular movements of the tympan.

4. In a device for preventing smutting in a web type of printing press where there is contact of a freshly imprinted portion of the web with the tympan sheet covering the tympan cylinder of the couple for effecting an imprint on the opposite side of the web from that bearing said freshly imprinted portion, and wherein oil is projected in finely atomized form for application to the tympan cylinder by an assembly of spray guns with an air manifold connected to said guns and a material manifold connected to said guns; the combination of a swinging support for said assembly adapted to hold said assembly in operative position relative to said tympan for projecting material in finely atomized form and to hold

said assembly away from said tympan to afford access to said couple, means operatively connected to said couple and said assembly for causing said guns to project said material in said finely atomized form when said assembly is in said operative position in given time relation with given angular movements of the tympan.

5. A device for timing the application of oil for preventing smutting in a web type of printing press where there is contact of a freshly imprinted portion of the web with the tympan sheet covering the tympan cylinder of the couple for effecting an imprint on the opposite side of the web from that bearing said freshly imprinted portion and wherein are a battery of spray guns alined along the tympan and so located as to project oil in finely atomized form for application to said sheet, and a rotating roller in contact with said sheet for distributing the sprayed particles of said oil over the surface of said sheet, the combination therewith of means for controlling the time of spraying in relation to the rotation of the tympan, including means driven by the couple to cause the guns to spray intermittently for given angular movements of the tympan.

6. A method of timing the application of oil for preventing smutting in a web type of printing press where there is contact of a freshly imprinted portion of the web with the tympan of the couple for effecting an imprint on the opposite side of the web from that bearing said freshly imprinted portion, and wherein there is an applying of the oil in minute particles over the surface of the tympan sheet covering the tympan cylinder, by projecting said oil in finely atomized form in a direction for application thereof to said sheet, and distributing said particles of oil over said sheet during the revolutions of said tympan, the combination therewith of the step of applying said fine spray of oil during only alternate given angular movements of the tympan cylinder.

7. A method of timing the application of oil for preventing smutting in a web type of printing press where there is contact of a freshly imprinted portion of the web with the tympan of

the couple for effecting an imprint on the opposite side of the web from that bearing said freshly imprinted portion, and wherein there is an applying of the oil in minute particles of the tympan sheet covering the tympan cylinder by projecting said oil in finely atomized form in a direction for application thereof to said sheet, including the distributing of said particles of oil over said sheet by effecting a slight squeezing action upon the elements of the surface of said sheet during all angular movements of the tympan; the combination therewith of the step of projecting said oil upon said pile surface of the roll only during alternate given angular movements of the tympan cylinder.

8. A method of timing the application of oil for preventing smutting in a web type of printing press where there is contact of a freshly imprinted portion of the web with the tympan of the couple for effecting an imprint on the opposite side of the web from that bearing said freshly imprinted portion, and wherein there is an applying of the oil in minute particles over the surface of the tympan sheet covering the tympan cylinder by projecting said oil in finely atomized form in a direction for application thereof to said sheet, and a distributing of said particles of oil over said sheet; the combination therewith of the step of applying said oil during only alternate given angular movements of the tympan cylinder.

9. A timing device for controlling the operation of spraying means having liquid and air supply means in a printing press, comprising a spring 35 pressed valve connected to the air supply means, a cam for intermittently operating said valve, drive means operatively connected to the cam and to an operating part of the press, a cam support adjustably connected to a fixed part of the press and operatively carrying the cam, a valve support carrying said valve and adjustably connected to and carried by said cam support for maintaining the adjusted relation of said valve and cam in all adjusted positions of said cam support.

VIRGIL G. GREEN.
